UNITED STATES PATENT OFFICE.

ROBERT E. HASTINGS, OF PHILADELPHIA, PENNSYLVANIA.

DEVICE FOR LAYING GOLD-LEAF.

SPECIFICATION forming part of Letters Patent No. 602,986, dated April 26, 1898.

Application filed October 8, 1897. Serial No. 654,511. (No model.)

To all whom it may concern:

Be it known that I, ROBERT E. HASTINGS, a citizen of the United States, residing in the city and county of Philadelphia, in the State 5 of Pennsylvania, have invented certain new and useful Improvements in Devices for Laying Gold-Leaf, of which the following is a specification.

In the art of gilding surfaces with gold leaf, 10 the leaf in the form of strips or ribbons, in connection with corresponding strips or ribbons of paper or similar material upon the face of which the leaf is mounted and adheres, is wound in the form of rolls upon suitable cylindriform wooden or other cores.

The leaf of these rolls is, in practice, applied directly to the surface to be ornamented, 15 by rolling the roll across the surface in such manner that the strip of paper and leaf, with the leaf beneath, is unwound from the roll, and deposited or laid upon the surface, to which the leaf adheres, and from which the paper is readily removable.

It is the object of my invention to provide 20 a neat, simple, and inexpensive, device, by or through which the rolls may be readily and conveniently held and manipulated by the workman in the application of the leaf to the surface to be decorated.

In the accompanying drawings I show and herein I describe a good form of a convenient embodiment of my invention, the particular subject-matter claimed as novel being herein-after definitely specified.

My invention comprehends,—for use in connection with the rolls described, the cores of which embody axial apertures or bores,—the provision of a pair of bearing plates adapted to be removably applied to opposite 25 sides of a core, and which have shanks adapted to project within the bore of said core for the support of said plates and to form an axle upon which the roll may rotate when the plates are held between the thumb and finger 30 of the user,—and further comprehends a retaining, tension, or brake device mounted in one of said holding plates, and provided with a shoe adapted to make contact with the exterior of the roll and prevent its untimely or 35 undue unwinding.

In the accompanying drawings, Figure 1 is a view in perspective of an ap-

paratus embodying my invention, illustrating the manner in which the same is held between the thumb and finger of the user. 55

Figure 2 is a central longitudinal sectional plan of the apparatus shown in Figure 1.

Figure 3 is a view in perspective of the devices shown in Figure 2, with the roll removed. 60

Similar letters of reference indicate corresponding parts.

In an application for patent filed by me on July 26, 1897, as Serial No. 645,968, I have illustrated and described several forms of apparatus or devices for laying gold-leaf, including the form of such device which constitutes the subject-matter of the present application; and in said former application I have claimed generically devices for laying gold leaf of which the device herein described is a type, and have also in said application specifically claimed a form of device therein disclosed. I do not, therefore, in the present application make generic claims upon devices of this class for laying gold leaf. 75

In the drawings,

A is the core, and a is the roll of leaf-provided paper mounted or wound upon it.

B and C are the holding plates, each provided as to its inner face with a shank,—the shanks being designated b and c, respectively. 80

The bodies of the holding plates are conveniently in the form of disks, and of such diameter as to permit of their being conveniently held between the thumb and finger of the user. 85

The shanks b and c project from opposite sides within the bore of the core, and together form an axle upon which,—the holding plates, 90 as shown in Figure 1, being held between the thumb and finger, and the roll being rolled along upon the surface to be decorated,—said roll will rotate as an axis.

The shank b is conveniently formed as a hollow boss, the exterior of which is approximately of the same diameter as the axial bore of the core, while the interior diameter of said boss is approximately equal to the exterior diameter of the shank c which is entered and capable of slight longitudinal movement within it. 95

b' is a spiral spring, shown as mounted upon the reduced inner end of the shank c, and 100

adapted, when the parts are assembled, to bear as to its free end against the base of the hollow interior of the boss *b*.

d is a slot or opening diametrically formed 5 through the body of one of the disks, conveniently the disk *B*, through which is passed and in which is seated free for longitudinal movement, the shank *d'* of a brake device *D*.

This shank extends diametrically of the roll 10 beyond its periphery, its front end being, beyond said periphery, shown as turned inwardly to form a brake shoe *d*².

In the use of the device, the user, first releasing the brake, grasps the holding plates 15 between his thumb and finger, and, pressing the roll against the surface to be decorated, draws it across the same in the proper direction to uncoil the leaf-bearing strip of paper.

The holding plates are readily withdrawn 20 from a given core after its roll has been un wound, and applied to a core carrying a fresh roll.

The shank *d'* of the brake, which is normally somewhat larger than the opening *d* 25 formed in the holding plate, is longitudinally split so that said shank may be compressed within said aperture, and, when in place, will by reason of the expansion of its split parts against the wall of said opening, retain itself 30 temporarily in any position to which it may be adjusted.

In the operation of the device, the brake member, whenever the use of the device is 35 temporarily discontinued, is to be moved inward in order to cause the shoe to press against the periphery of the roll, to prevent it from uncoiling,—said brake being, as will be understood, self-retaining in any position of adjustment in which it may be set.

40 The function of the spring *b'* is to normally maintain the holder plates sprung slightly apart, so to speak, so that the inner faces of said plates will clear the side faces of the core,—with the result that when compression is applied to said plates by the thumb and finger of the user, they will be carried toward each other against the faces of the core, incidentally compressing the spring and retarding the rotation of the core upon the axle in 45 proportion to the force applied to the plates.

As a result of this arrangement the rotation of the roll in the manipulation of the de-

vice may be regulated to a nicety, and the strip of film unwound from the roll, and, in the process of application to the surface to 55 be decorated, drawn taut by tightening the grasp upon said holding plates and confining said roll against rotation, at such times as it may be desired to exert tension upon the unwound strip.

Having thus described my invention, I claim and desire to secure by Letters Patent—

1. In combination,—an axially-apertured core for a roll of gold-leaf,—a holding device 65 for said core which embodies a transverse slot and is engaged in the aperture of said core to constitute an axle upon which the core- 70 provided roll rotates,—and a brake consisting of a shoe provided with a bifurcated shank mounted in said slot, and adapted by its expansion against the wall of the slot to maintain itself and the shoe in selected positions of adjustment,—substantially as set forth.

2. In combination,—an axially-apertured 75 core for a roll of gold-leaf,—a pair of shank- provided holding plates one of which embodies a slot and the shanks of which are entered from opposite ends within the aperture of the core,—a separating spring acting to separate 80 the plates,—and a brake carried by one of the plates and acting upon the periphery of the roll, which consists of a shoe having a longitudinally split shank entered within the slot of the slotted plate,—substantially as and 85 for the purpose specified.

3. In combination,—an axially-apertured 90 core for a roll of gold-leaf,—a pair of shank- provided holding plates one of which embodies a slot and the shanks of which are entered 95 from opposite ends within the aperture of the core,—a separating spring acting to separate the plates,—and a brake consisting of a shoe provided with a bifurcated shank of a normal diameter exceeding that of the slot, entered and compressed within said slot,—substantially 95 as set forth.

In testimony that I claim the foregoing as my invention I have hereunto signed my name this 7th day of October, A. D. 1897.

ROBERT E. HASTINGS.
In presence of—
J. BONSALL TAYLOR,
F. NORMAN DIXON.
